UNITED STATES PATENT OFFICE.

BOSQUE M. WHITEKER, OF HASKELL, TEXAS.

GAME AND TOY APPARATUS.

1,282,342.

Specification of Letters Patent. Patented Oct. 22, 1918.

Application filed April 16, 1917. Serial No. 162,236.

To all whom it may concern:

Be it known that I, BOSQUE M. WHITEKER, a citizen of the United States, residing in the city of Haskell, county of Haskell, State 5 of Texas, have invented a new and useful Improvement in the Way of a Game and Toy Apparatus, of which the following is a full specification, reference being had to the accompanying drawings.

10 My invention relates to a game and toy apparatus of the class wherein balls or arrows and the like are thrown from a spaced distance at an object located and set up within the field of the throw for the purpose of 15 scoring according to the number of hits made or otherwise, and my invention has for its principal object the production of a game and toy apparatus of this character of new and unique design and which may be adapted 20 to several different forms of games, or which may be adapted for use as a toy, it being understood that the essence of my invention resides in the apparatus itself, and not in the adaptation of said apparatus to 25 any particular form of game or toy; and any particular game which may be referred to in the course of this specification and wherein my apparatus is employed is so referred to solely for the purpose of illustration 30 as a particular example of my apparatus in actual use. Another object of my invention is to construct such apparatus in a practical and substantial form, and best adapted to meet the requirements of actual 35 use. Other objects and advantages will appear in the course of this specification.

In the drawings, Figure 1 is a perspective side view of my invention; Fig. 2 is a detail of the paddle wheel shaft, paddle wheels 40 and release mechanism; Fig. 3 is a frontal elevation on the line 3-3 in Fig. 1; Fig. 4 is a detail of the paddle wheel release mechanism; Fig. 5 is a detail showing the method of mounting the paddles upon the shaft.

45 Similar numerals refer to similar parts throughout the several views.

Referring more particularly to the drawing, the working elements of my invention are housed within a suitable supporting frame, represented as a whole by A, made up of a plurality of vertical pillars as shown at 1, 2, 3, 4, 5, 6, 7, and 8, and a plurality of suitable horizontal cross rails as shown at 9, 9', 10, 10' and 11. A portion of the pillars 50 as 1, 2, 3, and 4 located at the back end of

the court may be extended upward as shown in the drawings and a roof 12 may be provided for the purpose of shielding the apparatus from the weather. The working elements of my apparatus are mounted within 60 this protected end of the frame A. Said working elements comprise a revolving shaft 13 journaled at each end in the standards 14 and 15, which latter may be mounted upon the rails 9' and 10' as shown; mounted 65 upon the shaft 13 are a plurality of polyhedral axle blocks as shown at 16 in Fig. 5, there being one such axle block for each of the paddle wheels, which paddle wheels will be hereinafter described. One end of each of 70 said axle blocks is extended to the side of its paddle wheel and is rounded at that end so as to form short hubs as shown at 17, 18, 19 and 20. Into each of said hubs, 17, 18, 19 and 20 are cut a plurality of shallow notches 75 as shown at 21, 22, 23 and 24 in Fig. 5, said notches being arranged in parallelism with the shaft 13. Upon the sides of each axle block are mounted paddles as shown at 25, 26, 27 and 28 in Fig. 5. The method of 80 mounting these paddles upon the axle block is unique and depends upon the form and design of the paddle itself as shown in detail in Fig. 5, wherein it will be noted that each paddle is formed with an outwardly 85 facing transversely disposed cleat at one end as shown at 29, 30, 31 and 32 in Fig. 5, and an inwardly facing transversely disposed cleat located toward the middle of the paddle as shown at 33, 34, 35 and 36 in Fig. 5; 90 the said cleats being so shaped and located that each respective outwardly facing end cleat on one paddle engages and locks into and with each inwardly facing transversely disposed medial cleat on the adjacent paddle, 95 by which dove-tail arrangement each set of paddles is securely locked onto their respective axle block without the use of nails, screws, or other permanent fastening, and are also as readily removed when desired. 100

A plurality of such paddle wheels as shown, at 37, 38, 39 and 40 may be mounted upon the shaft 13. Spring control latches 41, 42, 43 and 44 are provided to control the rotation of the paddle wheels 37, 38, 39, and 40 upon the shaft 13. These latch springs are of coil formation, the inner end of each coil as shown at 45 in Fig. 5, being attached to the shaft 13 adjacent to its respective paddle wheel as shown at 37 in Fig. 4, and the 110

outer end of the coil 46 being bent at right angles in parallelism with the shaft 13, and so disposed over the hub 17 as to play frictionally into and out of the notches 21, 22, 5 23 and 24 as the paddle wheel revolves, as shown in detail in Figs. 4 and 5. Each of the paddle wheels 37, 38, 39 and 40 is similarly provided with a like spring control latch; and attached to and extending from 10 each spring control latch run release cords 47, 48, 49 and 50, same being extended over pulleys as shown at 51, 52, 53, and connecting with a main release cord 54, which runs forward to the front of the court, and may 15 be secured to the rail 11 for the purpose of easy manipulation by the operator.

In the preferable construction of my apparatus, one paddle on each paddle wheel may be weighted, so that the free tendency 20 of the paddle wheels unrestrained by the control latches, will be to turn the weighted paddles downward, thereby normally maintaining the said paddle wheels in the same relative position when the control latches are 25 released. Back of my apparatus is adjusted any suitable apron catch 59 for the purpose of catching the objects thrown, as for instance the balls 60, 61, and 62 as shown, and in the case of balls, deflecting same into 30 the chute 63, and carrying them back to the operator at the front of the court. A shield 64 of height just sufficient to cover the lower paddles of the paddle wheels, is located immediately in front of the paddle wheels for 35 the purpose of stopping objects, as balls, arrows or the like, which may be thrown too low.

In operation it will be noted that as the paddle wheels 37, 38, 39 and 40 revolve upon 40 the shaft 13, the control latches 41, 42, 43 and 44 follow the peripheries of the hubs 17, 18, 19 and 20, the ends of said control latches dropping into the transverse notches formed on the hubs as the wheels revolve. 45 The frictional action of said control latches is adjusted to such tension relative to the unbalanced paddles 55, 56, 57 and 58 as to overcome the normal downward tendency of said weighted paddles, and so as to sustain the 50 paddle wheels at that point in the course of their revolution where the friction of the control latches falling into the hub notches is sufficient to overcome the momentum of the wheels. This principle is of service in 55 carrying out certain forms of games as will be hereinafter explained. Similarly, when the paddle wheels cease revolving and come to rest, and it is desired to return said paddle wheels to their original relative position, all 60 that is necessary is for the operator to pull upon the main release cord 54, whereby the control latches 41, 42, 43 and 44 are drawn away from the hubs 17, 18, 19 and 20, the stress of the main pull being transmitted 65 through the connecting cords 47, 48, 49 and

50, and the weighted paddles 55, 56, 57 and 58 gravitate to the bottom. Pads, as shown at 65 in Fig. 5, may be provided for the paddles, which pads may be permanently attached, or may be sleeved so as to be 70 readily removed or changed.

It is obvious that I have here designed a unique game apparatus, adapted likewise for use as a toy when made up in small size. It is likewise obvious that this apparatus as 75 such may be adapted to a variety of forms of games, or to a variety of forms of toys. As a ball game, for example, certain of the paddles, selecting say one each of each paddle wheel, may carry the figure of a 80 noted ball player as shown by the letters B C D and E in Fig. 3, and that ball player may stand as representative of any certain ball team or league, and the game may consist in the operator having five balls to throw 85 for the purpose of displacing any three of the figures by striking those paddles with the balls, thereby causing the wheels to revolve and displacing the figures originally shown with bare paddles, leaving only his 90 selected figure remaining in sight; or the game may consist in the operator knocking out any certain figure in a certain number of throws by striking that figure with the ball, and causing the wheel to revolve, or in 95 lieu of the figures the paddles may be numbered 1, 2, 3 and 4 on each wheel, and the game may consist in the operator, say in five throws, striking the wheels successively so that when the wheels come to a rest any 100 certain set of numerals will show along the faces of the paddles. These illustrations are given merely as such, and it is obvious that a great variety of combinations and forms of games may be played on this apparatus. 105 Likewise arrows or blunt javelins may be used as the percussive agency against the paddles; or where used as a toy, marbles may be employed.

While I have herein described a certain 110 specific form and design for the construction of the several parts of my invention, and the assembling of the same as a working whole, it is understood that I may vary from said construction in minor details, not 115 departing from the spirit of my invention, so as best to construct my apparatus to meet practical and various requirements.

For instance, while the drawings, show a four bladed paddle wheel, the number may 120 be increased or diminished by forming the axle blocks with faces to correspond to the number required. Also while the paddles are described as having "cleats" located thereon, such cleats may constitute part of 125 the integral formation of the paddles themselves.

What I claim is:

1. A game and toy apparatus comprising a frame; a shaft set therein; rotatable, 130

polyhedral axle blocks mounted endwise on the shaft; demountable paddles locked to the faces of the axle blocks.

2. A game and toy apparatus comprising a frame; a shaft set therein; rotatable, polyhedral axle blocks mounted endwise on the shaft; demountable paddles locked to the faces of the axle blocks; and releasable means of control over the paddles.

10 3. A game and toy apparatus comprising a frame; a shaft set therein; rotatable, polyhedral axle blocks mounted endwise on the shaft; unbalanced, demountable paddles locked to the faces of the axle blocks; and 15 releasable means of control over the paddles.

4. A game and toy apparatus, comprising a frame; a shaft set therein; rotatable polyhedral axle blocks mounted endwise on the shaft; unbalanced, interlocking, demountable paddle locked concentrically, outstandingly and transversely around the faces of the axle blocks; and releasable means of control over the paddles.

5. A game and toy apparatus, comprising a frame; a shaft set therein; polyhedral axle blocks, having extended hubs bearing longitudinal, peripheral grooves, rotatably mounted on the shaft; paddles adjusted endwise and transversely to the faces of the 20 axle blocks, said paddles being so formed as to automatically interlock when placed in

position; a spring latch attached to the shaft adjacent to each axle block, the outer free end thereof having frictional engagement with the hub grooves aforesaid; a release 35 cord for each spring latch.

6. A game and toy apparatus comprising a frame; a shaft set therein; a plurality of paddle wheels rotatably mounted on the shaft, each wheel being composed of an 40 axle block polyhedral on one end and bossed on the other end to form a hub bearing longitudinal, peripheral grooves, a paddle for each side of the polyhedron, one paddle relatively heavier, and all formed and cleated 45 so as to automatically interlock endwise around the polyhedron; a spring latch for each axle block, one end thereof attached to the shaft, the other frictionally engaging the hub grooves aforesaid; a release cord attached to each spring latch; a main release 50 cord connecting with the several release cords and extending to the forward end of the frame; a shield located in front of and covering the lower row of paddles; a catch 55 apron located at the back; a chute leading from the catch apron to the front of the court.
